DESIGN FOR A CHAIR

Carlyle Norman Alexander, New Rochelle, N. Y.

Application January 21, 1947, Serial No. 136,280

Term of patent 14 years

(Cl. D15—1)

To all whom it may concern:

Be it known that I, Carlyle Norman Alexander, a citizen of the United States of America and resident of New Rochelle, county of Westchester, and State of New York, have invented a new, original, and ornamental Design for a Chair, of which the following is a specification, reference being had to the accompanying drawings, forming part thereof.

Fig. 1 is a front elevation of a chair showing my new design;

Fig. 2 is a side elevation of the chair shown in Fig. 1 viewed from the right side of the chair as there shown;

Fig. 3 is a top plan view of the chair shown in Fig. 1; and

Fig. 4 is a bottom plan view of the chair shown in Fig. 1.

I claim:

The ornamental design for a chair, as shown.

CARLYLE NORMAN ALEXANDER.
